US0D1055883S

(12) **United States Design Patent** (10) **Patent No.:** **US D1,055,883 S**
(45) **Date of Patent:** **** Dec. 31, 2024**

(54) **ELECTRONIC COMMUNICATIONS DEVICE**

(71) Applicant: **Relay, Inc.**, Raleigh, NC (US)

(72) Inventors: **Matthew Newton**, Park Ridge, IL (US);
Julianna Probst, Chicago, IL (US);
Kyle Buzzard, Vicksburg, MI (US);
Dave Conroy Joseph, St. Charles, IL (US); **Michael DiVerde**, Ten Mile, TN (US)

(73) Assignee: **Relay, Inc.**, Raleigh, NC (US)

(**) Term: **15 Years**

(21) Appl. No.: **29/934,244**

(22) Filed: **Mar. 25, 2024**

(51) **LOC (14) Cl.** **14-03**

(52) **U.S. Cl.**

USPC **D14/137**

(74) *Attorney, Agent, or Firm* — Relay, Inc.

(57) **CLAIM**

The ornamental design for an electronic communications device, as shown and described.

DESCRIPTION

FIG. 1 is a perspective view of a first embodiment of an electronic communications device showing our design;

FIG. 2 is a front view thereof;

FIG. 3 is a back view thereof;

FIG. 4 is a first side view thereof;

FIG. 5 is a second side view thereof;

FIG. 6 is a top view thereof; and

FIG. 7 is a bottom view thereof.

FIG. 8 is a perspective view of a second embodiment of an electronic communications device showing our design;

FIG. 9 is a front view thereof;

FIG. 10 is a back view thereof;

FIG. 11 is a first side view thereof;

FIG. 12 is a second side view thereof;

FIG. 13 is a top view thereof; and,

FIG. 14 is a bottom view thereof.

Broken lines, where shown, are used to illustrate portions of the electronic communications device which form no part of the claimed design.

1 Claim, 14 Drawing Sheets
